ATTORNEY.

UNITED STATES PATENT OFFICE.

EARL M. WITHERELL, OF DULUTH, MINNESOTA, ASSIGNOR OF ONE-HALF TO F. A. PATRICK & COMPANY, OF DULUTH, MINNESOTA, A CORPORATION OF MINNESOTA.

FABRIC DRYING AND SHAPING DEVICE.

1,318,470.

Specification of Letters Patent.

Patented Oct. 14, 1919.

Application filed May 26, 1917. Serial No. 171,135.

To all whom it may concern:

Be it known that I, EARL M. WITHERELL, a citizen of the United States, residing at Duluth, in the county of St. Louis and State 5 of Minnesota, have invented certain new and useful Improvements in Fabric Drying and Shaping Devices, of which the following is a specification, reference being had therein to the accompanying drawing.

10 This invention relates to fabric drying devices and has special reference to such for the drying of hosiery and the like.

The principal object of the invention is to provide means whereby quicker and better 15 results may be accomplished than heretofore known in the art.

Another object is to provide means whereby the drying element may be forced through as large a proportion of the object 20 being dried as possible.

Another object is to provide simple means whereby different sized forms may be interchanged with the least labor and annoyance possible.

25 Another object is to provide means whereby even distribution of the drying element is accomplished throughout the plurality of forms being simultaneously employed.

30 Other objects and advantages of the novel construction will appear in the further description of the device.

In the accompanying drawings forming part of this application and in which like 35 reference characters indicate like parts,

Figure 1 is a front elevation of a fragmentary portion of an installation embodying my invention.

Fig. 2 is a vertical transverse section of 40 one of the form coupling means, and

Fig. 3 is an enlarged transverse sectional view on the line A—B, Fig. 1, showing a stocking on the form.

Referring to the drawings, 1 represents a 45 working shelf or table through which the form supporting branch pipes 2 extend, they being connected with the horizontally extending manifold conduit or pipe 3.

The pipe 3 is graduated in size, diminishing 50 from its source of supply to the extreme opposite end and may be made to support any desired number of branch pipes 2, I having shown three thereof in the drawings, as a convenient number for illustrating the 55 invention.

At each point of reduction of the pipe 3, it is formed an inclined portion 4, it occurring only upon the upper side of the pipe and through which inclined portion the branch pipes 2 communicate and are fixed, the 60 upper and lower sides of the pipe 3 being parallel between said branch pipes. This is for the purpose of providing as direct and uniform circulation as possible of the air employed as a drying element and which is 65 forced through the pipes in any desired manner.

The upper end of each branch pipe 2 has the front and rear walls 5 and 6 respectively thereof, inclined upwardly toward each 70 other forming a tapered discharge nozzle, as clearly illustrated in Fig. 2. The front wall 5 of the nozzle has a partly cutout portion 7 therein, the lower end of which is made to normally extend slightly beyond a plane 75 with the face of the front wall and upon the outer face of the portion 7 is fixed a projecting substantially semi-spherical knob 8, which is designed to act as a lock or catch for the lower end of the hosiery form 9, 80 when the latter is applied to the free end of the branch pipe.

The lower end 10 of the form 9 is shaped to coincide with the co-operating nozzle end of the pipe 2, the front wall thereof being 85 provided with a suitable hole 11 therethrough, which registers with the knob 8 when the form is placed upon the nozzle, and which engagement is designed to be sufficient to prevent the form from being accidentally 90 displaced or removed from the nozzle and still provide simple means whereby a slight pressure of the finger of the operator upon the knob 8 will disengage it from contact with the form and allow the latter to be 95 freely removed.

The hosiery form 9, as illustrated in Figs. 1 and 2, is composed of interwoven open mesh wire of a metal suitable for the purpose and not susceptible to corrosion, as the 100 garments being dried upon such forms are usually placed thereupon in a damp or moist state.

The form 9 in cross-section is of a diamond shape, as illustrated in Fig. 3 and is 105 made of two like sections of the wire employed, the abutting side edges of the wire sections being soldered together and overlapped by a V-shaped metal binding piece 12, the outer opposed faces of which are in 110

a plane with the outer walls of the form so as to provide a smooth and even surface upon the form.

The four side walls of the form being straight and flat result in a positive obtuse angle 13, upon either side through the medial line of the form. Thus when the garment is removed from the form it will have fixed therein a central crease caused by said angles, thus producing an individual characteristic to the hose dried upon a form of this character and which establishes its identity.

This diamond shape of form is also material in the matter of strength to resist collapsing stress and that without the necessity of a central wall through the form.

By using a woven wire for the form, it is evident that the greatest possible area of the garment is simultaneously exposed to the action of the drying element, as the latter may contact the entire inner surface of the garment with the exception of the exceedingly small places where the humps of wire forming the meshes contact same. It is further obvious that where cold air is used as a drying element, the necessity of its contacting substantially the entire surface of the garment and passing therethrough, is essential. It is well known that in some kinds of fabric the drying with comparatively cold air is far superior to that of hot air, and with this construction of form, results heretofore impossible are accomplished.

If found preferable, in lieu of a non-corrosive metal being used in the construction of the forms as above described, said forms may be made of common iron or other metal and subsequently enameled with porcelain or the like to prevent objectionable chemical action when contacting the damp hose, and produce a form upon which the objects being dried may be applied and removed with the least friction possible as porcelain is known to have a smooth and particularly desirable surface for the purpose.

Having thus described my invention what I claim and desire to secure by Letters Patent is,

1. A hosiery drying and shaping device comprising an air supply manifold pipe graduated in size, upwardly extending curved branch pipes spaced apart upon the manifold pipe, one at the juncture of each step in the graduation of the pipe, tapered nozzles upon the free ends of the branch pipes, open forms having tapered shanks

to co-engage with the nozzles, and adjustable locking means for holding the forms upon the branch pipes against accidental removal, substantially as and for the purpose described.

2. A hosiery drying and shaping device comprising an air supply manifold pipe having the upper wall thereof successively stepped, forming graduations in the size thereof, an upwardly extending branch pipe at the juncture of each step in the graduation of the pipe and garment receiving forms carried by the branch pipes for the purpose described.

3. A drying and shaping device of the character described comprising an air supply manifold pipe graduated in size, an upwardly extending branch pipe at the juncture of each step in the graduation of the pipe, tapered nozzles upon the free ends of the branch pipes, hollow open forms having tapered shanks to co-engage with the nozzles and means for holding the forms upon the branch pipes against accidental removal.

4. In a hosiery drying and shaping device of the character described, a manifold supply pipe having its upper wall successively stepped forming graduated sizes thereof; hollow undivided perforated drying forms and branch pipes at each step of the graduations in the manifold pipe which communicates with the forms whereby air under uniform pressure is simultaneously supplied to the entire area of all of the forms.

5. In combination a horizontally disposed air supply pipe graduated in size, a plurality of upwardly extending hollow undivided single-walled perforated drying forms spaced longitudinally upon the pipe and communicating with the interior thereof whereby air may be forced under uniform pressure and volume through fabric mounted upon all of the forms.

6. In combination a horizontally disposed air supply pipe graduated in size, a plurality of upwardly extending perforated drying forms spaced longitudinally upon the pipe and communicating with the interior thereof whereby air may be forced under uniform pressure and volume through fabric mounted upon all of the forms.

In testimony whereof I hereunto affix my signature in the presence of two witnesses.

EARL M. WITHERELL.
